UNITED STATES PATENT OFFICE.

BENJAMIN F. BLAKEMAN AND ALVIS W. CRAVER, OF GREENSBORO, NORTH CAROLINA;
SAID BLAKEMAN ASSIGNOR TO SAID CRAVER.

COPYHOLDER.

Application filed January 11, 1927. Serial No. 160,467.

This invention relates to a copy holder adapted to be supported on a typewriter desk, table, or other flat surface, for the use of stenographers, typists, or the like.

5 The object of the invention is to provide a simple, practical and inexpensive device, which may be conveniently adjusted to hold a note book, or other copy, securely in any desired position with the front cover folded 60 back, together with any leaves which may have been previously copied, and which is also provided with improved means for engaging and holding the succeeding leaves as they are turned back, after the notes thereon 65 10 have been copied or transcribed. The device is also provided with independent means for supporting a bunch of envelopes or cards in convenient position to be copied.

15 The specific construction of the invention 20 and the advantages resulting therefrom will be more particularly described in connection with the accompanying drawing, which illustrates the same in its preferred form.

In the drawing:

25 Figure 1 is a front elevation of the copy holder in operative position.

Figure 2 is a central longitudinal section thereof.

30 Figure 3 is a rear elevation of the copy holder with the base broken away.

Figure 4 is a horizontal section thereof.

The device, which constitutes the subject matter of the present invention, comprises an inverted U-shaped member 5, having arms 35 6 secured to its lower extremities. These arms extend outwardly with their outer portions turned downwardly, as shown at 7, and terminating in transversely disposed feet 8. These feet are far enough apart so that they 40 may rest on the surface of the desk or table, one at each side of a typewriter, thus insuring the utmost stability to the copy holder. The feet are preferably provided with pads 9 so as not to mar or scratch the surface. 45 The arms 6 are adjustably connected with the member 7 in any suitable manner. In the present embodiment of the invention, each arm is provided with holes 10, in one of which the extremity of the member 5 is inserted. 50 This extremity is threaded to receive clamping nuts 11, one of which is disposed on each side of the arm 6.

The arm 6 and member 5 constitute a base on the upper part of which a plate 12 is 55 adjustably supported. This plate may be

made from a sheet of metal, rectangular in shape, and having a portion 13 bent rearwardly upon itself and formed with a transverse corrugation or groove 14 for receiving the upper portion of the member 5. The rearwardly bent portion 13 is secured to the front portion of the plate above the member 5 by a bolt and nut 15, or other suitable fastening means, and below the groove 14 a bolt 16 extends from the front portion of the plate 60 through the rearwardly folded portion, and is provided with a wing nut 17, which may be turned to adjust the pressure of the plate against the member 5 which supports it. This adjustment will usually be such that the plate 65 will be frictionally held in any desired position, but may be easily tilted about the upper part of the member 5 as an axis.

A spring clip 18 is secured to the upper part of the plate 12, and is provided with a 70 tongue 19, which extends transversely across the front face of the plate to secure a note book 20, or other copy thereto. Ordinarily, the bottom cover of the note book 20 will be clamped underneath the tongue 12. The clip 75 18 is provided with outwardly diverging ears 21, which may be grasped between the fingers for releasing or inserting the copy book. The rear ear 21 may be integrally or otherwise secured to the rear lap 13 of the 80 plate.

The lower end of the rear lap 13 extends 85 below the bolt 16, and is curved rearwardly, as shown at 22, to form an approximately cylindrical surface which extends for somewhat more than 180°. The edge is turned in, as at 23, and rotatably receives a spring rod or wire 24 forming a frame with sides 25, approximately of the same shape as the curved portion of the plate 22. These sides 90 are integrally connected together at 26, and are curved at 27 to fit over the curved portion 14 of the plate. This wire frame, when sprung into the position shown in full lines in Figure 2, will be under sufficient tension to clamp 95 the backwardly turned cover of the note book 20 and any used leaves that may be turned backwardly with the cover, and as each succeeding page is copied, it is turned backwardly about the frame by a rhythmic motion 100 of the back of the hand, and is pressed against the concave surface of the curved portion 22, whereby it is retained.

The lower front end of the plate 12 is 105 turned rearwardly, as at 28, to form a bear-

- ing for the rod or wire 29, which has curved ends 30. The back-turned portion 28 engages the wire 29 with sufficient friction to hold it in any position to which it is adjusted.
- 5 The wire 29 may, therefore, be turned so that the curved extremities 30 will engage over the lower ends of the leaves of the book 20, but the note book 20 may be removed and the curved ends 30 may be used as a pocket to receive a bunch of cards or envelopes to be copied.

From the foregoing description, it will be seen that we have provided a copy holder which rests upon the surface of the desk or table, and may be moved to any position convenient for the copyist. The plate 12 and its attachments may be used for supporting a note book, a plurality of loose sheets, a bunch of envelopes, or cards, or, in fact, anything 20 which is to be copied or transcribed. The holder is capable of universal adjustment, and its various attachments are adapted to hold the same securely.

While we have shown and described in detail the preferred form of the invention, it is obvious that various modifications may be made in the various details thereof without any material departure from the salient features thereof as defined in the claims.

30 What is claimed is:

1. In a copy holder, a supporting base including a bar having a round horizontal portion, a plate supported for rotative adjustment about said horizontal portion as an axis, 35 said plate being folded to form a front portion and a contiguous rear portion, said rear portion being formed with a transverse groove to receive the round horizontal portion of said bar, means connected with the front and rear portions of the plate to adjust the pressure on the bar so as to hold the plate in any position to which it is adjusted, and means for clamping the copy to said plate.

2. In a copy holder, a supporting base including a bar having a round horizontal portion, a plate adjustable about said bar as an axis, means for clamping a note book to the front face of said plate, said plate having a back with a rearwardly curved portion, a 50 spring frame hinged to the back and movable into interfitting relation to the back to secure the leaves of a note book, which is clamped to the front face of the plate, when said leaves are turned backwardly about the upper end of the plate.

3. In a copy holder, a supporting base including a bar having a round horizontal portion, a plate adjustable about said bar as an axis, means for clamping a note book to the 60 front face of the plate, said plate having a back with a rearwardly curved portion, a spring frame hinged to the back and adapted to be swung into a position contiguous to the concave surface of said curved portion, said 65 spring frame being curved to correspond to

the surface of the back, and means cooperating with the tension of the spring frame to latch the latter in such contiguous position so as to secure leaves of a note book, which is clamped to the front face of the plate, when 70 said leaves are turned backwardly about the upper end of the plate.

4. In a copy holder, a supporting base including a bar having a round horizontal portion, a plate adjustable about said bar as an 75 axis, said plate being folded to form a front portion and a contiguous rear portion, said rear portion being formed with a transverse corrugation to receive the round horizontal portion of said bar, means for securing the plate in any position to which it is adjusted, means for clamping a note book to the front face of the plate, said plate having a back with its lower portion curved rearwardly, a spring frame hinged to the lower edge of the 80 back and adapted to be swung into a position contiguous to the concave surface of the back, said spring frame being curved to fit into the concavity of the back and also having a curved portion to fit around the convex side 85 of said corrugation, thus constituting a spring latch to hold the frame against the back so as to secure leaves of a note book, which is clamped to the front face of the plate, when 90 said leaves are turned backwardly about the 95 upper end of the plate.

5. In a copy holder, a plate, means for clamping a note book to the front face thereof, said plate having a back with its lower portion curved rearwardly, a spring frame 100 hinged to the back and movable into interfitting relation to the curved part of the back to secure leaves of a note book, which is clamped to the front face of the plate, when 105 said leaves are turned backwardly about the upper end of the plate.

6. In a copy holder, a plate, means for clamping a note book to the front face thereof, said plate having a back with its lower portion curved rearwardly, a spring frame 110 hinged to the back and adapted to be swung into a position contiguous to the concave surface of the back, said spring frame being curved to correspond to the surface of the back, and means cooperating with the tension of the spring frame to latch the latter in such contiguous position so as to secure leaves of a note book, which is clamped to the front face of the plate, when 115 said leaves are turned backwardly about the upper end of the plate.

7. In a copy holder, a plate having a rearwardly curved back portion, means for clamping a note book to the front face of the plate, a curved frame pivoted to the back and cooperating with the curved back of the plate to engage and hold such leaves of the note book as are turned backwardly and about the upper end of the plate, and independent means adjustably mounted on the lower part 120 125 130

of the plate and having fingers adapted to hold down the remaining leaves.

8. In a copy holder, an inverted U-shaped frame, a plate mounted for adjustment about 5 the intermediate portion of said frame as an axis, means for clamping a copy to the plate, outwardly extending supporting arms secured to the lower extremities of said frame, each arm being longitudinally and rotatably

adjustable with respect to said frame, the 10 outer portions of said arms being turned downwardly and having feet adapted to rest on a flat surface.

In testimony that we claim the foregoing as our own, we have hereto affixed our sig- 15 natures.

BENJAMIN F. BLAKEMAN.
ALVIS W. CRAVER.
